(57) **CLAIM**

The ornamental design for a handle, as shown and described.

DESCRIPTION

FIG. 1 is a top perspective view of the handle of our design; FIG. 2 is a rear view thereof;

FIG. 3 is a bottom view of the handle of FIG. 1;

FIG. 4 is a front view of the handle of FIG. 1;

FIG. 5 is a top view of the handle of FIG. 1; and, FIG. 6 is a left side view of the handle of FIG. 1, the right side being a mirror image thereof.

The broken lines in the figures form no part of the claimed design.

1 Claim, 6 Drawing Sheets---
